UNITED STATES PATENT OFFICE

155,771

DESIGN FOR A RAILWAY BRAKE BEAM

Walter H. Baselt, Flossmoor, Ill.

Application April 9, 1947, Serial No. 138,268

Term of patent 14 years

(Cl. D66—3)

To all whom it may concern:

Be it known that I, Walter H. Baselt, a citizen of the United States, residing at Flossmoor, Illinois, have invented a new, original, and ornamental Design for a Railway Brake Beam, of which the following is a specification, reference being had to the accompanying drawings, forming a part thereof, wherein:

Figure 1 is a top perspective view of the railway brake beam embodying my novel design;

Figure 2 is a perspective end view of the beam;

Figure 3 is a top plan view of the beam;

Figure 4 is a front view of the beam; and

Figure 5 is a fragmentary rear view of the beam.

I claim:

The ornamental design for a railway brake beam, substantially as shown.

WALTER H. BASELT.
